(57) **CLAIM**

The ornamental design for a vacuum hose tubing adapter, as shown.

DESCRIPTION

FIG. 1 is a front view depicting a vacuum hose tubing adapter.

FIG. 2 is a top view depicting the vacuum hose tubing adapter.

FIG. 3 is a left side view depicting the vacuum hose tubing adapter.

FIG. 4 is a right side view depicting the vacuum hose tubing adapter.

FIG. 5 is a bottom view depicting the vacuum hose tubing adapter.

FIG. 6 is a rear view depicting the vacuum hose tubing adapter.

FIG. 7 is a front perspective view depicting the vacuum hose tubing adapter; and,

FIG. 8 is a rear perspective view depicting the vacuum hose tubing adapter.

1 Claim, 5 Drawing Sheets
